UNITED STATES PATENT OFFICE.

FREDRICK J. McGAVISK, OF GRAND HAVEN, MICHIGAN.

OIL-RETAINER FOR BARRELS OF FIREARMS.

1,229,991.

Specification of Letters Patent. Patented June 12, 1917.

Application filed October 30, 1916. Serial No. 128,567.

To all whom it may concern:

Be it known that I, FREDRICK J. McGAVISK, a citizen of the United States, residing at Grand Haven, in the county of 5 Ottawa, State of Michigan, have invented certain new and useful Improvements in Oil-Retainers for Barrels of Firearms; and I do hereby declare the following to be a full, clear, and exact description of the invention, such as will enable others skilled 10 in the art to which it appertains to make and use the same.

The present invention has for its object to provide a device of this character constructed in such a manner that when applied to the barrel it will serve to retain a quantity of oil within the barrel indefinitely so as to prevent rust accumulating within the barrel.

20 A further object of the invention is to provide a device of this character so constructed that the device when in place will positively retain the oil within the barrel, but said device can be easily and quickly removed when desired.

A still further object of the invention is to provide a device of this character provided with means for absorbing the jar of the firing pin when the hammer is released.

30 With these and other objects in view this invention resides in the novel features of construction, formation, combination and arrangement of parts to be hereinafter more fully described and claimed in the accompanying drawing in which:—

Figure 1 is a side elevation of a barrel partly in section showing the same equipped with the device.

Fig. 2 is a longitudinal sectional view 40 through the retainer used in the breech end of the barrel.

Fig. 3 is an end view of the retainer used on the muzzle of the barrel.

Fig. 4 is a plan view of the muzzle retainer.

Referring to the drawing 1 indicates the barrel of a gun, and in the breech end thereof is engaged the retainer 2, said retainer comprising a shell 3 which has its priming 50 opening 4 unobstructed so that when the hammer is released the firing pin thereof can enter the opening. It will be understood that the device can be used with any type of firearm barrel.

55 Engaged in the shell 3 with a coil spring 4' the outer end of which has bearing there-

against is a disk 5 which receives the impact of the firing pin when the hammer is released. The front end of the spring 4' is engaged with the disk 6, said disk being slidably mounted in the shell 3 and is provided with a central threaded opening 7 in which is engaged a threaded rod 8, said rod having its front end secured in the rubber plug 9, said plug being adapted to engage 65 in the bore of the barrel 1 so as to retain the oil in the barrel when the gun is resting in a position with the muzzle elevated. Removably engaged with the shell 3 is a cap 10, so that access can be had to the interior 70 thereof.

The retainer 11 for the muzzle of the barrel consists of a plate 12, said plate being substantially circular in shape and has hingedly connected at diametrically opposite points plates 13 and 14, the former having a slot 15 formed therein for receiving the sight 16 carried by the barrel 1. When the sight is engaged with the slot 15 it is obvious that longitudinal movement of the 80 plate 13 relative to the barrel will be prevented, but the plate can be readily removed when desired.

The plate 14 lies under the barrel 1, while the plate 13 engages the upper surface 85 thereof, and at which time the packing 17 carried by the plate 12 will close the muzzle of the barrel. The rear end of the plate 13 is provided with lateral wings 18 which are adapted to be bent around the barrel and 90 have their free ends provided with hooks 19, the purpose of which will appear later.

The plate 14 has its rear end terminating in spaced fingers 20, and pivotally and adjustably mounted between the fingers is a 95 lever 21, said lever having connected to its inner end a cross bar 22, said bar having its ends 23 adapted to detachably engage the hooks 19 of the wings 18. Thus it will be seen that when the hooks 19 are engaged 100 with the ends 23, that the lever 21 can be swung rearwardly thereby swinging the plate 12 rearwardly with the result that the plate 12 will be firmly engaged with the muzzle of the barrel so as to close the same to 105 prevent oil contained in the barrel from leaking from the muzzle should the barrel be inverted.

What is claimed is:—

1. An oil retainer for firearm barrels comprising a shell removably engaged in the breech of the barrel, a plug yieldably con-

- nected with the shell for engaging the bore of the barrel, and means removably engaged with the barrel for closing the muzzle thereof.
- 5 2. An oil retainer for firearm barrels comprising a shell removably engaged in the breech of the barrel, said shell having its priming opening unobstructed, disks mounted in the shell, a coil spring disposed 10 between the disks, one of said disks being disposed adjacent the priming opening, a rod threaded in the other disk, the outer end of said rod having a plug carried thereby for yieldably engaging the bore of the 15 barrel, the disk adjacent the priming opening serving to receive the impact of the
- firing pin of the hammer, and means for closing the muzzle end of the barrel.
3. An oil retainer for gun barrels comprising a plate for closing the muzzle of the 20 barrel, plates hingedly connected to said plate, means for detachably connecting the plates to the barrel, and means removably engaged with the breech end of the barrel, said means operating in conjunction with 25 the plate to trap oil within the barrel.

In testimony whereof, I affix my signature, in the presence of two witnesses.

FREDRICK J. McGAVISK.
